UNITED STATES PATENT OFFICE.

JOHN PATRICK FALLOON, OF PHILADELPHIA, PENNSYLVANIA.
TIGHTENER MEANS FOR PROJECTION AND OTHER SCREENS.

1,121,081.

Specification of Letters Patent.

Patented Dec. 15, 1914.

Application filed December 6, 1913. Serial No. 805,000.

To all whom it may concern:

Be it known that I, JOHN P. FALLOON, a citizen of the United States, residing at the city of Philadelphia, in the county of Philadelphia and State of Pennsylvania, have invented certain new and useful Improvements in Tightener Means for Projection and other Screens, of which the following is a specification.

10 My invention has relation to tightener-means for projection and other screens; and in such connection it relates particularly to the constructive arrangement of the said means and of the operation thereof for the defined purpose.

15 The moving picture exhibition screens have been a constant source of trouble requiring attention to maintain them taut to obtain the best results of the projected photo-
20 play or sketch thereon, and if not so maintained effects result which are peculiar, not those ordinarily required, and which are most noticeable to observers of the photo-displays on the screen. Various expedients
25 have been resorted to for the purpose of obviating buckling or bulging of screens in the past, but thus far with but only more or less satisfactory results.

30 The principal object of my present invention is to provide a tightener-means for screens, which is arranged so as to be simply manipulated from one point to effectually maintain a mirrograph or other type of screen of a moving picture exhibition always taut and thus to enhance appreciably the true show effects of a photo-play or sketch upon the screen.

35 The nature and scope of my present invention will be more fully understood from the following description taken in connection with the accompanying drawings forming part hereof, in which—

40 Figure 1, is a plan view of a framed screen having a tightener-means, embodying the essential main features of my said invention in application thereto; and Fig. 2, is a cross-sectional view on the line $\alpha-\alpha$, of Fig. 1, showing in detail the arrangement of my said tightener-means.

45 Referring to the drawings α , is a projec-

tion-screen connected with two of the sides and one of the ends to the top of a framing a^1 . This framing a^1 , in the lower part of each of the sides of the same is grooved at a^2 , and in which sides are mounted the 55 tongues b^1 , of a perforated stretcher-cross-bar b . This bar rides on a series of vertical pins c , secured into the cross-strips a^3 , and a^4 , of the framing a^1 . The stretcher bar b , is provided with a series of bolts e , partially threaded and extending through the cross-strip a^4 . These bolts carry nuts e^1 , for manipulating the stretcher-bar b , up and down in the grooves a^2 , of the said framing a^1 . The lower end of the said 65 screen is fastened to the stretcher-bar b , so that slack in the screen can be quickly taken up by simple manipulation of the nuts e^1 , on the bolts e , as will be apparent from Fig. 1 of the drawings.

70 Having thus described the nature and object of my invention, what I claim as new and desire to secure by Letters Patent is:—

The combination with a projection-screen, of a framing having a central support in 75 fixed relation with the top and base members of said framing and the latter formed into an extension having grooves in the sides, a stretcher cross-bar mounted in said grooves and riding on pins extending 80 through said bar and in fixed relation with the base-member of said framing and base-member of said extension, tightening-bolts connected with said stretcher cross-bar and extending through the base member of said 85 extension and removable-means connected with said bolts for tightening and loosening the same in connection with said extension and said screen connected at the top and sides with said framing and at the bottom 90 with said stretcher cross-bar, substantially as and for the purposes described.

In witness whereof, I have hereunto set my hand in the presence of the two subscribing witnesses.

JOHN PATRICK FALLOON.

Witnesses:

THOMAS M. SMITH,
HELEN S. HOLT.
